UNITED STATES PATENT OFFICE.

CARL HEROLD, OF PITTSBURG, PENNSYLVANIA.

IMPROVEMENT IN PACKING SHOE-BLACKING.

Specification forming part of Letters Patent No. 130,917, dated August 27, 1872.

Specification describing a certain Improvement in Packing Shoe-Blackening, invented by CARL HEROLD, residing at Pittsburg, in the county of Allegheny and State of Pennsylvania.

The object of my invention is to provide a cheap and convenient mode or means for packing the ordinary pasty shoe-blacking of commerce, which is now almost universally put up in shallow tin boxes, which, being expensive, comparatively, greatly enhance the price of the blacking thus packed. Flexible pouches of rubber and tinfoil it has been suggested to use for this purpose; but these devices are open to the same objection of comparative high cost. My improvement consists in putting shoe-blacking upon the market packed in the guts of animals, which will add but a trifle to the cost of the blacking.

Figure 1 is an elevation of a package of blacking put up in accordance with my invention. Fig. 2 is a transverse section thereof.

The same letters of reference are used in both figures in the designation of identical parts.

The blacking is packed in suitable lengths

of animal guts A, which are then firmly tied up at both ends, presenting the appearance of a sausage. Each package should be wrapped in paper to prevent the grease or oil upon the outer surface of the package from soiling the hands in handling it. The blacking thus packed will retain its moisture, and consequently remain in a proper plastic state for a great length of time. In this condition it may be sold by the pound, each purchaser or user providing himself with a small saucer or other shallow vessel into which to empty portions of the package from time to time for use.

What I claim as my invention, and desire to secure by Letters Patent, is—

As a new article of manufacture, shoe-blacking packed in animal guts, substantially as and for the purpose specified.

In testimony whereof I have signed my name to this specification in the presence of two subscribing witnesses.

CARL HEROLD.
